UNITED STATES PATENT OFFICE

THOMAS F. STACY, OF PIQUA, OHIO, ASSIGNOR TO THE FRENCH OIL MILL MACHINERY CO., OF PIQUA, OHIO

VALVE DEVICE

Application filed May 10, 1929. Serial No. 362,074.

This invention relates to valve devices for fluid operated presses and the like, and particularly to the control of fluids utilized to operate a press.

5 An object of the invention is to generally improve and simplify the construction and operation of such valve devices.

Another object of the invention is to provide an improved valve device of this type, 10 with which a plurality of operations of the press may be obtained by a single controlling element; with which the controlling element may be easily operated into its different 15 operating positions with a minimum of effort; with which the operating or controlling member will be held automatically in the different operating positions into which it may be moved; and with which discharge of fluid under pressure from the source of supply directly 20 into the exhaust connection during operation of the valve controlling element from one operating position to another will be prevented.

A further object of the invention is to provide an improved valve device of this type 25 which will be relatively simple, compact, efficient, economical in use, practical and inexpensive.

Various other objects and advantages will 30 be apparent from the following description of two embodiments of the invention, and the novel features will be particularly pointed out hereinafter in connection with the appended claims.

35 In the accompanying drawings:

Fig. 1 is a longitudinal, sectional plan through a valve device constructed in accordance with this invention;

40 Fig. 2 is a side elevation of the same, with certain parts in section approximately along the line 2—2 of Fig. 1;

Fig. 3 is a transverse, sectional elevation through the same, with the section taken approximately along the line 3—3 of Fig. 1;

45 Fig. 4 is another transverse, sectional elevation of the same, with the section taken approximately along the line 4—4 of Fig. 1;

Fig. 5 is a side elevation of another 50 valve device also constructed in accordance

with the invention, but illustrating another embodiment thereof;

Fig. 6 is a sectional plan of the same, the section being taken approximately along the line 6—6 of Fig. 5;

55

Fig. 7 is a transverse, sectional elevation of the same, with the section taken approximately along the line 7—7 of Fig. 6;

Fig. 8 is another transverse, sectional elevation of the same, the section being taken 60 approximately along the line 8—8 of Fig. 6; and

Fig. 9 is a sectional diagram illustrating the relation of the main valve element to its 65 seats, which is the same in both illustrated embodiments of the invention.

In the embodiment of the invention illustrated in Figs. 1 to 4, and 9, the improved valve device includes a casing 1 having a longitudinally extending chamber 2 therein 70 which is closed at its ends by removable plugs 3 and 4. The casing is also provided with a lateral extension 5 having therein separate auxiliary chambers 6 and 7 which are in communication with the chamber 2 at different points along the same. The extension 5 is provided with a port 8 (Figs. 2 and 4) to which is connected a pipe 9 for supplying a fluid under a relatively low pressure to the chamber 6.

80

The extension 5 is also provided with a second and separate port 10 (Figs. 2 and 3) to which is connected a pipe 11 for supplying a fluid under a relatively high pressure to the chamber 7. The casing is also provided, 85 intermediate of its ends, with a port 13 to which is connected a pipe 14, leading to the fluid operated press to be operated, for supplying the press with an operating fluid under pressure. The casing 1 is also provided, adjacent one end of the chamber 2, with an exhaust port 15 to which is connected a suitable exhaust pipe 16. The chamber 6 communicates with the chamber 2 at one end of the latter, and the exhaust port 15 is 90 arranged at the opposite end of the chamber 2.

95

The port 13 may be referred to as an intermediate port in that it opens into the chamber 2 at a point intermediate the ends of the 100

same and between the low pressure port 8 and the exhaust port 15. The chamber 2 is provided with an annular seat 17 and through the passage or area enclosed by this seat, 5 fluid must pass from the low pressure inlet chamber 6 to the press connection port 13. Similarly, a valve seat 18 is arranged across the chamber 2 between the intermediate port 13 and the exhaust port 15. The seats 17 10 and 18, in this particular example, are annular seats facing in opposite directions away from one another.

A valve element 19 extends into the chamber 2 of the casing 1 from one end thereof, 15 such as through one of the removable plugs 4, and is slidably mounted for reciprocation in the plug 4 and also in a cavity or recess 20 in the opposite end plug 3. This valve element is provided with a closure section 21 20 adjacent its inner end which moves into and out of closing engagement with the seat 18 when the valve element is reciprocated. The valve element is also provided with a second closure section 22 which similarly is shifted 25 into and out of closing relation to the seat 17 by reciprocation of the valve element.

The two closure sections 21 and 22 may be shoulders, flanges or enlarged sections on the valve element, and they are spaced apart 30 along the length of the valve element a distance greater than the distance between the annular seats 17 and 18, so that when one closure section is in engagement with its related seat, the other closure section will be 35 well away from its related closure seat. The valve element, by its reciprocation, will thus connect the press connection port 13, which is the intermediate port, alternately with the exhaust port 15 and the low pressure inlet 40 port 8. A suitable packing gasket 23 may be provided for the valve element where it passes through the removable plug 4 to the exterior of the casing.

The area of the valve element at the section 45 which passes through the packing gasket 23 is greater than the area enclosed by the seat 18, as shown exaggerated in the diagram of Fig. 9, and there is therefore a definite force outward of the valve element when the closure section 21 is in engagement with the seat 18. This outward force or pressure will 50 of itself hold the valve element in its end position in which the seat 18 is closed, when the valve has been operated into that position.

If now the valve element 19 is reciprocated in the opposite direction to carry the section 21 away from seat 18 and carry the section 22 into engagement with the seat 17, as 60 shown in Fig. 1, it will be noted that the valve element will be similarly held in its other closed position. This holding of the valve element in its other end position, as shown in Fig. 1, is due to the fact that the area of 65 the valve element in the section which passes

through the gasket 23 is less than the area enclosed by the seat 17, as also shown exaggerated in the diagram of Fig. 9. It will therefore be observed that the valve element will be pressure held in both of its extreme 70 positions.

In order that there be no direct possible communication between the opposite ends of the chamber 2 during operation of the valve element, which would cause a temporary loss 75 of fluid under pressure from the inlet chamber 6 directly to the exhaust port, the valve element may also be provided with piston sections 24 and 25 which extend toward one another from the closure sections 22 and 80 21 respectively.

These piston sections are of a size to pass freely into and along, but yet close the passages that are enclosed or defined by the seats 17 and 18, one piston section being in the passage defined by its related seat when the other piston section is entirely out of the passage defined by its related seat. The lengths of these piston sections, measured in the direction of the length of the valve element, will 85 90 be such that each piston section will not leave its related passage when moving in an opening direction until the other piston section has entered, or is at the entrance to, its related passage, as shown in Fig. 1. The piston 95 sections should move freely along their related passages, and while there may be some slight leakage along the same, nevertheless they effectively prevent any material loss of fluid between the end ports 8 and 15 during 100 movement of the valve element.

In order to assemble a valve element having the oppositely facing closure sections 21 and 22, the valve element may be made in two parts A and B. The part A consists of one 105 end of the element with its closure section 21 and piston section 25, and a stem portion 26 which extends through a longitudinally extending passage in the other part B. The part B comprises a sleeve which reciprocates 110 in the removable plug 4 and carries the closure section 22 and the piston section 24. The stem portion 26 is provided with a shoulder 27, Figs. 1 and 6, which engages with an internal seat in the inner end of the part B to prevent leakage along the interior of the sleeve forming the part B. The stem portion 26 extends entirely through the sleeve of part B, and is threaded to receive an operating head 28.

The forked end of this head 28 is connected by pivot pin 29 to an operating handle or lever 30, which is also pivotally connected by pin 31 to one end of a link 32, the link being pivotally connected at its other end by a pin 33 to a lug extending from the casing 1. The head 28 when threaded along the stem 26 engages with the sleeve of the part B and forces the latter against the shoulder 27 of the stem, so as to unite the two parts 120 125 130

A and B into a rigid structure and to close the passage through the sleeve of the part B.

A gravity operated, free check valve 34 (Figs. 2 and 4) is disposed in the chamber 6 in alignment with the low pressure inlet port 8, and is mounted and guided for reciprocation in a removable plug 35. The inner or lower end of the valve 34 has radial arms or guides 36 which slidely fit a seat ring 37, and the valve 34, intermediate of its ends, is provided with a closure section 38 which moves into and out of engagement with the seat ring 37 when the valve 34 reciprocates endwise of itself.

The valve opens freely by any excess of pressure in the pipe 9 over that in chamber 6, so that fluid may pass freely from the pipe 9 into the chamber 6 and thence into the chamber 2, but when pressure in the chamber 6 exceeds the pressure in the pipe 9, the valve 34 will automatically close for a purpose which will appear shortly. To enable the valve 34 to slide freely in the plug 35, the valve may have one or more passages 39 connecting the end received in the plug 35 with the sides of the valve element adjacent the closure section 38, but at the upper side thereof, as shown in Figs. 2 and 4.

The auxiliary chamber 7 communicates with chamber 2 at a point between the two seats 17 and 18, and will always be directly in communication with the press connection port 13 as shown in Figs. 1 and 3, regardless of the position of the valve element 19.

A valve seat ring 40 (Figs. 2 and 3) is disposed across the chamber 7 for controlling communication with the port 10, and the casting 1 is provided with a removable plug 41 which is in alignment with the ring 40. A hollow, cup-shaped member 42 is slidely mounted in the inner end of the plug 41, and is provided at its closed end with a tail 43 which is slidely mounted or guided in a passage 44 of a partition across the plug 41, as shown in Fig. 3. A disk 45 is provided in the plug 41 at the opposite side of the partition and bears against the tail 43.

A helical spring 46 is compressed between the disk 45 and the opposite and removable end 47 of the removable plug 41. A screw 48 may be threaded through the removable end 47 of the plug 41 to engage a disk 49 which serves as an adjustable abutment for the outer end of the spring 46. By adjustment of the screw 48, the extent of compression of the spring 46 may be varied. The plug 41 may have a vent 50 in the section housing the spring.

The member 42, at its open end, mounts another valve member 51 which is adapted to reciprocate and rotate in the open end of the member 42. At its lower end the member 51 is provided with a closure section 52, which engages with the seat ring 40 to close communication between the chamber 7 and the

high pressure inlet port 10. The member 51 may have one or more grooves 53 running lengthwise thereof, and also endwise across the inner end of the same, so that the same pressure will be exerted on all faces of the member 51 which are within the member 42. The member 42 may also be engaged by a gasket element 54 which is secured in position against a seat by the removable plug 41.

The members 42 and 51 together form a valve member in two sections whose upward movement is yieldingly opposed by the spring 46, and the inner section or member 51 may rotate and reciprocate within the outer section or member with comparative freedom. With such freedom of movement for member 51, cutting of the valve seat ring 40 and of the closure section 52 during use of the valve device will be prevented.

When the pressure in the auxiliary chamber 7 at the discharge side of seat 40, which is always in communication with the press connection port 13, reaches a predetermined pressure, the members 42 and 51, whose exposed area at the lower ends is larger than the area enclosed by the seat ring 40, will be forced upwardly against the action of the spring 46, and fluid under a relatively high pressure may then pass freely from the pipe 11 through the auxiliary chamber 7 and press connection port 13 to the press to continue to build up pressure in the press.

In relating the operation of this valve device, let it be assumed that the valve element 19 is in the position shown in Figs. 1 and 2. At that time, the closure section 22 will shut off from the intermediate or press connection port 13, all communication with the low pressure inlet pipe 9, that is, with the end port 8. The intermediate port 13 will then be in direct communication with the exhaust port 15 and the pressure in the press will be only the back pressure on the exhaust pipe 16.

The pressure in the intermediate section of the chamber 2 will be very small, and will correspond to the pressure in the exhaust pipe. Consequently, there will be no force acting to shift the high pressure change valve 42 and 51 upwardly except the pressure within the seat ring 40. The passage in the seat ring 40 is relatively small, and such upward pressure, because of the relatively small area of the passage within the ring 40, will be insufficient to overcome the downward pressure of the spring 46, with the result that the seat ring 40 will be held closed.

If now it is desired to admit pressure to the press, the valve handle 30 is operated to the left (in Fig. 2) and during that movement, the closure section 22 of the valve element 19 will move to uncover the seat 17, and the closure section 21 will move into closing engagement with the seat 18. During this movement, the piston section 24 associated with the closure section 22 will not leave the

passage enclosed by the seat 17 until the piston section 25 associated with the other closure section 21 has entered the passage enclosed by the seat 18, and therefore the fluid 5 under pressure entering from the auxiliary chamber 6 cannot pass directly to the exhaust. The fluid under pressure from pipe 9 enters freely because flow in this direction is permitted by the free check valve 34.

10 The press (not shown) will then operate until the resistance increases, at which time the pressure in the intermediate section of the chamber 2 increases toward approximately the pressure in the low pressure supply pipe 9. When the pressure in the intermediate section of the chamber 2, and in the auxiliary chamber 7 which always is in communication therewith, increases to a predetermined pressure, less than the pressure 15 in pipe 9 of course, the valve members 42 and 51 will be lifted by the pressure thereon in the chamber 7, and immediately fluid under high pressure will flow from pipe 11 through chambers 7 and 2 into the press connection pipe 14 until the pressure at the press reaches that of the ingoing high pressure.

As the pressure in the chamber 2 builds up above that of the low pressure fluid supply, the free check valve 34 will seat itself 20 automatically, so as to prevent reverse flow into the low pressure supply pipe 9. After the desired high pressure has been maintained for the desired interval, the valve handle 30 may be operated to the right, in 25 Fig. 2, to return the valve element to the position shown in Figs. 1 and 2, whereupon the pressure in the press pipe 14 will be released, owing to its connection to the exhaust port 15, and original conditions will be 30 established.

Considering now the embodiment of the invention illustrated in Figs. 5 to 8, and 9, the construction is similar to that described in connection with Figs. 1 to 4, except for 35 details which will now be explained. Parts in Figs. 5 to 8 which correspond to those found in Figs. 1 to 4 will be given the same reference characters. The valve element 19, (Figs. 5 to 8) at its outer end is pivotally 40 connected by a pivot pin 55 to links 56, which in turn are pivotally connected by a pin 57 to the operating lever 30.

The lever 30 is also connected by a pivot pin 58 to a bracket 59 secured to one end of 45 the casing 1a which is generally similar to the casing 1 of Figs. 1 to 4. The valve element 19 is the same as explained for Figs. 1 to 4. The low pressure check valve element 34a is similar to the valve 34, except that the 50 guide arms 36 are omitted. The automatic change valve for controlling the admission of a fluid under high pressure is somewhat different than that explained for Figs. 1 to 4, in that the high pressure itself tends to hold 55 its own controlling valve closed.

Referring particularly to Fig. 7, the two section valve member formed of members 42 and 51 of Figs. 1 to 4 is replaced by a valve stem or member 60 which extends loosely through the passage of the ring 40 and slidingly through the walls 61 and 62 defining part of the chamber 7. The lower end 63 of the stem 60 reciprocates in a removable plug 64 which compresses suitable packing 65 between it and the removable end wall 62. 70 The valve stem 60 has a closure section 66 which engages with the seat ring 40 at the high pressure supply end of the ring, so that the pressure at the upper end of the chamber 7 will normally hold the valve stem 60 in 75 closed position. The upwardly projecting end of the valve member 60 passes through suitable packing 67 and a plug 68 which is disposed in or threaded into a recess in the upper side of the casing. A plug 69 is re- 80 movedly secured in the open end of this cavity in the upper face of the casing 1a, and this plug 69 has a piston chamber 70 at its open lower end, in which reciprocates a piston 71 mounted on the projecting end of the 85 valve member 60. A spring 46 is compressed between a washer 72 fitted over the upwardly projecting end of the stem or valve member 60, and the closed end of the plug 69. The plug 69 may have suitable vents 73 and 74 90 which permit free movement of the piston in the chamber 70.

A small conduit or channel 75 connects the lower end of the cavity into which the plug 69 is threaded with the intermediate section 95 of the chamber 2, so that the pressure on the under face of the piston 71 at all times corresponds to the pressure in the chamber 7 at the discharge side of seat 40 and in the pipe 14 which leads to the press. When the pressure in the intermediate section of the chamber 2 increases by the inflow of fluid under low pressure, as explained in connection with Figs. 1 to 4, the upward force acting 100 on the piston 71 of the valve member 60 105 will increase.

When the force acting on the piston 71 in a direction to lift the valve member 60 reaches a predetermined pressure, it will overcome the spring 46 and the downward pressure on the portion of the stem or valve 110 115 60 which is the chamber 7 above the seat ring 40, and thereupon the valve member 60 will be operated upwardly into open position. The fluid under high pressure will then flow 120 through the auxiliary chamber 7 into the chamber 2, and thence to the press to cause an operation thereof as explained for Figs. 1 to 4.

When the valve handle 30 is operated to 125 shut off the supply of low pressure fluid, as when it is in the position shown in Fig. 1 which is the opposite position from that shown in Fig. 6, the pressure in the intermediate section of the chamber 2 will fall by 130

reason of its connection to the exhaust, and thereupon the spring 46 will force the valve member 60 downwardly into closed position. While the valve member 60 is in closed position, the pressure in the upper part of the chamber 7 will assist spring 46 in securely holding member 60 in closed position on its seat ring. The operation of the embodiment of the invention illustrated in Figs. 5 to 8, and 10 9, is otherwise the same as explained for Figs. 1 to 4, and 9.

It will be obvious that various changes in the details, which have been herein described and illustrated in order to explain the nature 15 of the invention, may be made by those skilled in the art within the principle and scope of the invention as expressed in the appended claims.

I claim:—

20 1. A valve device for fluid operated presses and the like, comprising a casing having a closed chamber with ports for three pipe connections spaced apart along the same and two annular seats controlling communication between the intermediate port and the other ports, a valve element extending into said chamber from outside and at its inner end movable back and forth within the chamber to position spaced sections thereof alternately 25 in closing positions across said seats, one of said annular seats being smaller than the other and the section of the valve element in the chamber at the point where it passes out of said chamber having a cross sectional area 30 of a size between the areas enclosed by the said seats.

25 2. A valve device for fluid operated presses and the like, comprising a casing having a closed chamber with ports for three pipe connections spaced apart along the same and two annular oppositely facing valve seats controlling communication between the intermediate port and the other ports, a valve element extending into said chamber from the exterior of the casing and having spaced closure sections, said element being mounted for reciprocation to carry said closure sections alternately into and out of engagement with their seats and thus connect the intermediate 35 port alternately with the two end ports, the section of the valve element which passes through the casing having less cross sectional area than the area enclosed by the adjacent seat, and both of such areas being greater than the area enclosed by the other seat, whereby when a source of pressure is connected to the port at the end of the casing where the valve element enters the casing, the intermediate port is connected to a press, and the opposite end port is connected to an exhaust connection, the valve element will be locked by pressure in both positions.

30 3. A valve device for fluid operated presses and the like, comprising a casing having a closed chamber with ports for three pipe

connections spaced apart along the same, a source of low pressure fluid connected to one end pipe connection, a source of high pressure fluid and a press connection connected to the middle port, an exhaust connection to the other end port said chamber having two annular valve seats in said chamber controlling communication between the intermediate port and the other ports and facing the adjacent ends of said chamber, and a unitary 70 valve element slidably mounted solely for reciprocation in said chamber and having spaced closure sections rigidly connected to one another in the ends of said chamber and which alternately engage said seats during 75 reciprocation of the valve element, said valve element having an operating section extending out of said chamber at the end connected to said low pressure said element also having a piston portion adjacent each closure section 80 which enters and passes through the adjacent valve seat during movement of said element in a direction to carry the adjacent closure section into closed relation on its related seat, said piston sections having diameters filling 85 the passages in related seats and lengths such that the passage through each seat will be closed while the passage through the other seat is open, whereby direct communication between the end ports will be avoided in all 90 reciprocating movements of said valve element.

4. A valve device for fluid operated presses and the like, comprising a casing having a closed chamber with ports for three 100 pipe connections spaced apart along the same, a source of low pressure fluid connected to one end pipe connection, a source of high pressure fluid and a press connection connected to the middle port, an exhaust connection to the other end port said chamber having two annular valve seats in 105 said chamber controlling communication between the intermediate port and the other ports and facing the adjacent ends of said chamber, a valve stem extending through said casing into said chamber through the end connected to said source of low pressure and mounted for endwise sliding reciprocation, only said stem having flanged sections fixed 110 thereon and engageable alternately with their adjacent seats during reciprocation of said stem, whereby communication between the intermediate port and the other ports will be alternately established by reciprocation of 115 said stem, said stem having piston sections immediately adjoining the flanged sections and extending toward one another and slideable through the seats which the flanged sections close, each piston section having a 120 diameter filling the passage in its related seat and a length such that during opening of the passage through the valve seat in which it is moving, that piston section will prevent communication through that passage until the 125 130

- 5 piston section associated with the other seat has entered the passage through that other seat, and will then move out of its seat to open the passage, whereby direct communication between said end ports will be prevented.
- 10 5. A valve device for fluid operated presses and the like, comprising a casing having a closed chamber with a plurality of ports for pipe connections spaced apart along the same, and two annular oppositely facing valve seats controlling communication between the end ports and an intermediate port, a valve element extending into said chamber from the 15 outside and reciprocating in said casing and having closure sections spaced apart along its length a distance greater than the distance between said seats, whereby when said valve element is reciprocated, said closure sections 20 will engage alternately with said seats, the end portion of said valve element having one closure section being detachably and rigidly connected to the portion having the other section, and said closure sections and the section passing out of said chamber all being 25 of different sizes with the closure sections the largest and smallest, whereby the valve element will be pressure held at each limit of its reciprocation.
- 30 6. A valve device for fluid operated presses and the like, comprising a casing having a closed chamber with a plurality of ports for pipe connections spaced apart along the same, and two annular opposite facing valve seats 35 controlling communication between the end ports and an intermediate port, a valve element reciprocating in said casing and having closure sections spaced apart along its length a distance greater than the distance between 40 said seats, whereby when said valve element is reciprocated, said closure sections will engage alternately with said seats, one end portion of the valve element with its closure section having a threaded stem which passes 45 through an endwise passage in the other portion having the other closure section, said valve element extending exteriorly of the casing, and operating means detachably connected to the outer end of the valve element.
- 50 7. A valve device for valve operated presses and the like, comprising a casing having a closed chamber with a plurality of ports, for a plurality of pipe connections, spaced apart 55 along the same and also aligned, annular, oppositely facing valve seats controlling communication between the intermediate port and the end ports, said casing having passage therethrough into said chamber in alignment with said seats, a member having a closure section engageable with one of said seats and having a stem passing through both seats and exteriorly of the casing through said passage, said stem having a shoulder thereon, a sleeve confined on said 60 stem against said shoulder and having a sec-

tion engageable with the other valve seat to close the same when said stem is in a position to open the passage through the other valve seat, said member and sleeve together forming a reciprocating valve element which carries said closure sections alternately into engagement with their related seats, and means connected to the outer end of said valve element for reciprocating the same.

75 8. In a valve device for fluid operated presses and the like, an automatic high pressure change valve comprising a casing having a passage therethrough, a valve seat in said passage, a valve member in said casing movable into and out of engagement with said seat to close or open said passage, resilient mechanical means for urging said valve member against the direction of fluid flow in said passage into closed position, the portion of said valve member in said passage at the discharge side of said seat having an area greater than the area engageable with said seat, whereby when the back pressure in said passage at the discharge side of said seat reaches a predetermined value, it will force said valve into open position and permit fluid flow through said seat and said passage, said valve member including a cup-shaped section with its open end facing said valve seat, 80 slidable toward and from said seat, and engaged and operated by said resilient means towards its seat, and an inner section freely slidable and rotatable in the cavity of said cup and having a reduced portion directly engageable with said seat to close the same 85 when both of said sections are forced toward the seat, whereby cutting between the valve seat and valve member will be avoided, one of the sections of the valve member having a 90 passage leading to the inner end of the inner section, whereby the pressure on the inner section will be equalized, and the inner section 95 will be free to rotate and slide in the outer section.

100 9. In a valve device for fluid operated presses and the like, a casing having a chamber with ports spaced apart endwise thereof, a valve element shiftable in said chamber and controlling communication between the end ports and the ported section of the chamber between the end ports, a source of fluid under a relatively low pressure connected solely to one end port, a source of fluid under a relatively high pressure connected solely to an intermediate port, an exhaust pipe connected to the other end port, a press connection to said ported chamber section, so as to be in direct communication with said source of high pressure fluid, a check valve in the passage for low pressure fluid to said chamber and preventing fluid flow from said chamber into said passage, a physically separate check valve in the passage through which fluid from said high pressure source enters said chamber and urged into open position 105

110

115

120

125

130

by the pressure upon a part only of the area of one end thereof by fluid from said source of high pressure which is trying to enter said chamber, a yielding mechanical device 5 forcing said separate check valve into closed position and against said pressure on said partial end area, the balance of said end area being always directly exposed to the pressure in said chamber section, whereby 10 when the back pressure in said chamber section, caused by resistance offered by the press, upon said balance of end area, and the pressure on the partial end area by the shut off high pressure fluid, are sufficient to overcome the closing pressure of said mechanical 15 means on that separate valve, that valve will open automatically and admit high pressure fluid directly to said chamber section and thence to said press connection.
